United States Patent Office

Des. 220,490
Patented Apr. 20, 1971

220,490

MARINE TERMINAL BLOCK

Lowell Abeles, 77 Zaccheus Mead Lane,
Greenwich, Conn. 06830

Filed Jan. 8, 1970, Ser. No. 20,832

Term of patent 14 years

Int. Cl. D13—03

U.S. Cl. D26—1

FIG. 1

FIG. 2

FIG. 1 is a top plan view of a marine terminal block of my new design;

FIG. 2 is a left end elevation of a marine terminal block;

FIG. 3 is a front elevation of a marine terminal block;

FIG. 4 is a rear elevation of a marine terminal block; and

FIG. 5 is a right end elevation of a marine terminal block.

I claim:

The ornamental design for a marine terminal block, substantially as shown and described.
